(57) **CLAIM**

The ornamental design for an optical component for an LED lamp, as shown and described.

DESCRIPTION

FIG. 1 is a perspective view of a first optical component for an LED lamp showing our new design;

FIG. 2 is an end view of the component of FIG. 1;

FIG. 3 is a perspective view of a second optical component for an LED lamp showing our new design;

FIG. 4 is an end view of the component of FIG. 3;

FIG. 5 is a side view of the components of FIGS. 1 and 3;

FIG. 6 is a top view of the components of FIGS. 1 and 3; and,

FIG. 7 is a bottom view of the components of FIGS. 1 and 3.
